UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

CONDENSER

Application filed January 16, 1930. Serial No. 421,198.

This invention relates to steam condensers of the surface type and an object of the invention is to provide a condenser structure embodying fluid tight leakage preventing connections between the tubes and the tube heads; novel means for accompanying expansion and contraction of the tubes of the condenser under the heat variances caused by fluctuating loads on the condenser, and weight distributing features whereby the weight of the condenser, tubes, water therein, etc. is distributed over a relatively wide area and in such manner as to relieve the turbine exhaust neck of much suspended weight.

More specifically the present invention comprehends the provision of a condenser structure wherein the hot well is supported directly from the foundation of the power plant and connected to the condenser shell by expansion joints to maintain fluid tight joints between the shell and hot well under all conditions and to relieve the shell, its supports and the turbine exhaust neck of the weight of the hot well and the water therein, thereby avoiding distortion of the turbine shaft by upthrust from the condenser when the latter is operating at "hot" or atmospheric exhaust condition. Further distribution of the weight of the condenser structure and consequently further upthrust elimination is provided in the condenser of the present application by providing support plates, for the tubes of the condenser, which are supported directly from the hot well and are free from connection with the condenser shell or its supports.

The present invention also comprises, in combination with the above enumerated features, means, preferably in the form of movable support plates, to accommodate expansion and contraction of the tubes under temperature variances, without affecting their connection with the tube heads; thereby permitting the expanding of both ends of the tubes into the tube heads and the consequent advantages of fluid tight joints and inexpensiveness of construction of such joints in comparison with the present approved type of packed joints between the tubes and the tube heads.

With these and other objects in view, as may appear from the accompanying specification, the invention consists in various features of construction and combination of parts, which will be first described in connection with the accompanying drawings, showing a condenser of the preferred form as embodied in the present invention, and the features forming the invention will be specifically pointed out in the claims.

In the drawings:

Figure 1 is a side elevation of a condenser constructed in accordance with this invention.

Figure 2 is a longitudinal section through the condenser.

Figure 3 is a vertical cross section through the condenser taken on the line 3—3 of Figure 1.

Figure 4 is a detailed fragmentary view illustrating the manner of connecting the tubes to the tube heads and their longitudinal bowing.

Referring more particularly to the drawings, the improved condenser comprises a shell 1 of any approved construction, having an exhaust steam inlet 2 through which the steam to be condensed enters the condenser. Water for cooling or condensing the steam passes through the longitudinally extending tubes 3 of the condenser, from the water box 4 to the water box 5. The condenser may be of either single or multiple pass construction without departing from the spirit of this invention. In Figure 2 a two pass condenser is illustrated and as is readily understood, in such condensers the circulating water passes from the water box 4 through a part of the tubes into the water box 5 and returns through other of the tubes to the water box 4, passing therefrom through the outlet 6.

In the present construction, the condenser shell 1 is supported by supports 7, and supporting springs 8 through the medium of the supporting feet 9 formed on the condenser shell and the hot well 10 which is in present type of approved constructions connected directly to the condenser shell and supported therefrom, is in the present invention supported independently of the shell 10 and directly upon the foundation or floor 11. The

hot well 10 is connected to the shell 1 by means of one or more expansion joints which permit of movement of the shell 1 relative to the hot well 10 without disrupting the fluid tight connection between these members and without interrupting the flow of condensate from the shell into the hot well.

The tubes 3 have their ends expanded into the tube heads 14 and they may be bowed intermediate the tube heads as indicated in Figure 4 or in any of the approved manners as disclosed in my companion application Ser. No. 412,481, filed December 7th, 1929. The bowing of the tubes intermediate their ends is provided to permit or accommodate expansion and contraction of the tubes under temperature variances within the condenser. Owing to the size of condensers of this type, the tubes are relatively long and it is necessary to provide means for supporting the tubes intermediate of the tube heads 14 and in the present invention support plate structures 15 and 16 are illustrated which not only support the tubes intermediate their ends but permit movement of the bowed portion of the tubes under expansion and contraction action.

In Figure 3 of the drawings the construction of the support plate structures is clearly shown and each support plate structure 15 or 16 comprises a pair of plates 17 and 18 which have arms 19 formed as a continuation of their lower portions. The arms 19 extend through the respective expansion joints 12 and into the hot well 10 where their lower ends are pivoted by means of pivotal pins 20 to suitable brackets 21 either formed upon or attached to the bottom of the hot well 10 so that the support plates will be supported from the hot well and its support independently of the shell 1 and its supports thereby further distributing the weight, not only of the condenser plates themselves but of the intermediate portion of the tubes and the water therein and relieving the turbine exhaust neck (not shown) of weight and further reducing upthrust action when the condenser is operating under "hot" or atmospheric exhaust conditions. The support plates 17 and 18 being pivotally mounted, and at a point farthest from the inlet of steam into the shell 1 are permitted to move upon their pivotal axis to accommodate expansion and contraction of the tubes 3 and by the location of their pivots their maximum scope of movement is at the portion of the condenser shell subjected to the highest temperatures. The pivoting plates 17 and 18 of each support plate structure 15 and 16 are urged into their inward or normal positions by means of a spring 22 and suitable rods 23 and 24.

In the drawings of the present application, the support plates 17 and 18 are shown of a patent construction, with the arms 19

extending into the hot well, and it is thereby understood that any of the various forms of mounting of the support plates as shown in my companion application hereinabove referred to may be employed without departing from the spirit of this invention, insofar as the said plates are supported independently of the condenser shell 1 and in such manner that their weight and the weight of the intermediate portions of the tubes will be distributed to the point of support of the plates and not to the shell 1.

The hot well 10 may be anchored to the floor or foundation 11 by any suitable type of anchoring means such as shown at 30, or it may be connected in any other manner to the foundation or floor so as to prevent vibratory or jumping action.

From the foregoing description taken in connection with the accompanying drawings 85 it will be apparent that an improved condenser structure has been provided in which fluid tight inexpensive connection between the tubes and the tube heads may be provided with novel and efficient means for supporting 90 the tubes and accommodating their movement under expansion and contraction, in combination with the distribution of weight of the condenser.

It will be understood that the invention is 95 not to be limited to the specific construction or arrangement of parts shown, but that this may be modified widely within the invention as defined by the claims.

What is claimed is:

1. In a condenser, a shell, spring supports therefor, a hot well rigidly supported independently of said shell, and an expansion joint between said hot well and shell.

2. In a condenser, a shell, spring supports therefor, a hot well rigidly supported independently of said shell, an expansion joint between said hot well and shell, tubes in said shell, and support plates for said tubes supported from said hot well.

3. In a condenser, a shell, tubes therein, spring supports for said shell, and support plates for said tubes supported independently of said shell.

4. In a condenser, a shell, tubes therein, 115 spring supports for said shell, and support plates for said tubes supported independently of said shell, said tubes being bowed to accommodate expansion and contraction thereof.

5. In a condenser, a shell, tubes therein, supports for the shell, and support plates for said tubes pivotally supported independently of said shell.

6. In a condenser, a shell, tubes therein, 125 supports for the shell, support plates for said tubes pivotally supported independently of said shell, and means for urging said support plates into normal position.

7. In a condenser, a shell, tubes therein, 130

5 supports for the shell, support plates for said tubes supported independently of said shell and movable independently of the shell to accommodate expansion and contraction of the tubes.

8. In a condenser, a shell, supports for the shell, tubes in the shell being bowed to accommodate expansion and contraction thereof, support plates for said tubes pivotally supported independently of said shell and movable independently of the shell to accommodate expansion and contraction of the tubes.

15 9. In a condenser, a shell, supports for said shell, tubes in said shell being bowed to accommodate expansion and contraction thereof, support plates for said tubes pivotally supported independently of the shell and movable in the direction of the bowing of the tubes upon expansion or contraction of the tubes, and means for urging said support plates into normal position.

25 10. In a condenser, a shell, supports for said shell, tubes in the shell being bowed to accommodate expansion and contraction thereof, support plates for said tubes pivotally supported independently of the shell and movable in the direction of the bowing of the tubes upon expansion or contraction of the tubes, said support plates being pivoted at a point whereby their maximum scope of movement will be at the part of the condenser subjected to highest temperature.

35 11. In a condenser, a shell, supports for said shell, tubes in the shell being bowed to accommodate expansion and contraction thereof, support plates for said tubes pivotally supported independently of the shell and movable in the direction of the bowing of the tubes upon expansion or contraction of the tubes, said support plates being pivoted at a point whereby their maximum scope of movement will be at the part of the condenser subjected to highest temperature and means for urging said support plates into normal position.

40 12. In a condenser, a shell, spring supports therefor, tubes in the shell, a hot well rigidly supported independently of said shell, an expansion joint between said hot well and shell, support plates for said tubes, said support plates being pivotally connected to said hot well.

45 13. In a condenser, a shell, spring supports therefor, tubes in the shell, a hot well rigidly supported independently of said shell, an expansion joint between said hot well and shell, and support plates for said tubes, said support plates being pivotally supported from said hot well whereby their maximum scope of movement will be at the part of the condenser subjected to highest temperatures.

50 14. In a condenser, a shell, spring supports therefor, tubes in the shell, a hot well rigidly supported independently of said shell, an ex-

pansion joint between said hot well and shell, support plates for said tubes, said tubes being bowed to accommodate expansion and contraction thereof, said support plates being movably supported by said hot well for movement relative to the hot well and shell upon expansion and contraction of the tubes.

55 15. In a condenser, a shell, supports therefor, a hot well rigidly supported independently of said shell and its supports, tubes in said condenser, one or more support plates for said tubes mounted for movement relative to the shell on a fixed axis.

60 16. In a condenser, a shell, supports therefor, a hot well rigidly supported independently of said shell and its supports, tubes in said condenser, one or more support plates for said tubes supported independently of the shell for movement on a fixed axis relative to the shell.

65 17. In a condenser, a shell, supports therefor, a hot well rigidly supported independently of said shell and its supports, tubes in said condenser, one or more support plates for said tubes supported from the hot well for movement relative to the shell on a fixed axis.

70 18. In a condenser, a shell, supports therefor, a hot well rigidly supported independently of said shell and its supports, tubes in said condenser, one or more support plates for said tubes supported from the hot well for movement relative to the shell on a fixed axis, and means for urging said support plates into normal position.

75 In testimony whereof I affix my signature.
JOHN F. GRACE.
